R. E. AYLWORTH AND L. WIERSMA.
MATCHED BOARD LAYER.
APPLICATION FILED FEB. 19, 1919.

1,313,664.

Patented Aug. 19, 1919.

UNITED STATES PATENT OFFICE.

RAY E. AYLWORTH AND LAMBERT WIERSMA, OF GRAND RAPIDS, MICHIGAN,
ASSIGNORS OF ONE-THIRD TO HARVEY E. KILMER, OF GRAND RAPIDS,
MICHIGAN.

MATCHED-BOARD LAYER.

1,313,664.

Specification of Letters Patent. Patented Aug. 19, 1919.

Application filed February 19, 1919. Serial No. 277,956.

To all whom it may concern:

Be it known that we, RAY E. AYLWORTH and LAMBERT WIERSMA, citizens of the United States, residing at Grand Rapids, in the county of Kent and State of Michigan, have invented certain new and useful Improvements in Matched-Board Layers; and we do hereby declare the following to be a full, clear, and exact description of the invention, such as will enable others skilled in the art to which it appertains to make and use the same.

This invention relates to improvements in board layers and has for one of its objects the provision of a device of this character, which is especially adaptable for laying tongue and groove boards, or to cause them to properly interlock with each other so that they can be conveniently nailed or secured in place.

Another object of this invention is the provision of a device of the above stated character which will force and hold the boards tightly together permitting a person to conveniently fasten them in place without the aid of other persons holding said boards while the fastening operation takes place.

A further object of this invention is the provision of a board layer of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:—

Figure 1 is a side elevation of a board layer constructed in accordance with our invention.

Fig. 2 is a vertical sectional view of the same.

Fig. 3 is a plan view illustrating the arm for engagement with the boards.

Fig. 4 is a detail view of a locking jaw.

Referring in detail to the drawing, the numeral 1 indicates an elongated hollow body having secured in one end thereof a shank 2

on which is formed an anchoring head 3. 55 The anchoring head 3 is provided with a pointed portion 4 and an anvil portion 5 so that the head can be readily hit with a suitable tool for driving the pointed portion into rafters or like portions of a building for anchoring the body against endwise movement in one direction.

A rack bar 6 having teeth 7 formed upon its upper face is slidably mounted within the body 1 and extends outwardly of the open 65 end thereof and has formed upon its ends a substantially U-shaped member 8 adapted to form relatively spaced arms. The ends of the arms have formed thereon heads 9 in which are formed slots or recesses 10 to receive the tongues formed upon the edges of 70 boards which are of the matched type or of the tongue and groove type.

The body 1 adjacent one end and on the upper face has struck up therefrom relatively spaced ears 11 and 12. The ear 12 is of a greater height than the ear 11 and has formed upon its edge notches 13. A lever 14 has one end thereof pivoted to and between the ears 11 and 12 and has formed upon its 80 pivoted end a head 15 having teeth 16 adapted to mesh with the teeth of the rack bar 6 for forcing said rack bar outwardly of the body and moving the free end of the lever downwardly or in the direction of the body. 85 A dog 17 is pivoted to the lever and has a sharpened end adapted to engage within the notches formed within the ear 12 for holding the lever against upwardly movement when the device is in use in pressing and holding boards together. The sharpened end of the dog is provided with a guard 18 adapted to ride against the outer face of the ear 12 to prevent the dog from moving out 90 of the path of the teeth during the operation 95 of the device.

When boards of the tongue and groove type have been placed in position upon their respective rafters and it is desired that they be moved in the direction of each other to cause the tongues and grooves to interlock, the pointed portion 4 of the head 3 is driven into a rafter and the tongue on the outermost board is received within the slots or grooves 10 of the heads 9 and by moving the free end of the lever in the direction of the body, the boards will be forced together or in the direction of each other causing the tongues to

- move within the grooves of the respective boards. At the same time the dog rides over the teeth upon the gear and will hold the lever against reverse movement so that the operator may then be free to nail or secure the boards in their proper position. When it is desired to remove the instrument from the boards, the dog is released from the teeth 13 and the lever is swung upwardly 10 causing the rack bar to be retracted in the body disengaging the head from the boards and the pointed end of the head 3 may be then disconnected from the rafter.
- From the foregoing description taken in connection with the accompanying drawings, it will be noted that a device has been provided which is especially adaptable for laying tongue and groove boards either as 15 flooring, ceiling or side walls.
- It is also to be noted that the device is simple and compact and can be conveniently used by a single person when desiring to assemble or force boards in close relation to each other upon their respective rafters.

While we have shown and described the 25 preferred embodiment of our invention, it will be understood that minor changes in construction, combination, and arrangement of parts may be made without departing from the spirit and scope of the invention as 30 claimed.

Having thus described our invention, what we claim is:—

A board layer comprising a hollow elongated body, a shank secured within one end 35 of said body, a head formed on said shank and having a pointed end and anvil face, a rack bar slidable in said body, means carried by said rack bar for engagement with a board, and means actuating the rack bar. 40

In testimony whereof we affix our signatures in presence of two witnesses.

RAY E. AYLWORTH.
LAMBERT WIERSMA.
